CLAIM

The ornamental design for a pillow, as shown and described.

DESCRIPTION

FIG. 1 is the front bottom perspective view of a pillow; FIG. 2 is the front elevation view of the pillow;

FIG. 3 is the rear elevation view of the pillow;

FIG. 4 is the right side view of the pillow;

FIG. 5 is the left side view of the pillow;

FIG. 6 is the top view of the pillow;

FIG. 7 is the bottom view of the pillow;

FIG. 8 is an environmental view, depicting the pillow in use; FIG. 9 is another environmental view, depicting the pillow in use; and,

FIG. 10 is yet another environmental view, depicting the pillow in use.

The broken lines illustrate the environment in which the pillow is used and form no part of the claimed design.
